UNITED STATES PATENT OFFICE.

GEORGE F. SIMONDS, OF FITCHBURG, MASSACHUSETTS.

ROLLER-SWAGING DIE.

SPECIFICATION forming part of Letters Patent No. 352,366, dated November 9, 1886.

Application filed April 8, 1886. Serial No. 198,256. (No model.)

To all whom it may concern:

Be it known that I, GEORGE F. SIMONDS, of Fitchburg, in the county of Worcester and State of Massachusetts, have invented certain 5 Improvements in Dies for Use in Machines for Making Rolled Forgings; and I hereby declare the following to be a full, clear, and exact description, reference being had to the accompanying drawings, making part of this specification, in which—

Figure 1 is a side elevation of a die illustrating my improved manner of forming the teeth on the working faces. Fig. 2 illustrates a modification of the same.

15 My invention relates to dies for making rolled forgings that are circular in transverse section, and especially adapted for use in the forging-machine patented by me June 9, 1885, No. 319,752, and is an improvement on the 20 dies for which patents were issued to me June 9, 1885, Nos. 319,754, 319,755, and 319,756, and has for its object to so make the die faces as to absolutely insure perfect rotation of the blank regardless of the direction 25 in which the dies may be moving; and to this end it consists in dies provided with working faces, wherein are cut raking or diagonally-pitched teeth to seize the heated blank to insure its proper relative movement to the 30 movement of the dies.

In order that those skilled in the art may make and use my invention, I will proceed to describe the exact manner in which I have carried it out.

35 In the said drawings, *a* represents a view of a die, the top being one of the spreading faces, as described in the patents hereinbefore mentioned. These spreading faces are provided with teeth *t*, which rake, after the

manner of saw-teeth, in the direction of the 40 travel of the die, and thereby are enabled to take a better hold upon the surface of the heated blank and absolutely insure its rotation.

In the modification shown in Fig. 2 the 45 spreading surface of the die-faces are provided with a tooth, *i*, having its point in a vertical line, and on each side of it a tooth or teeth, *i*, raking in opposite directions, which is a desirable form to be used when the blank 50 is to be submitted to a number of reciprocations of the dies.

I am aware that heretofore reciprocating dies for swaging-screws have been made with thread-forming surfaces arranged diagonal 55 to the die-face, and with the sides of said grooves having a pitch in one direction. Such grooves, however, constitute the forming-face of the die, while in my invention the grooves are transverse the die-face and perform only the function of forcing the blank 60 to rotate in the required time.

Having thus described my invention, what I claim as new, and desire to secure by Letters Patent, is—

1. Dies for machines for making rolled forgings, provided on their surfaces with transversely-arranged raking-teeth, for the purpose set forth.

2. Dies for machines for making rolled forgings, provided on their surfaces with series of transversely-arranged oppositely-raking teeth and an intermediate vertical tooth, substantially as described.

GEO. F. SIMONDS.
